The ornamental design for a jaw rest for patient use during dental procedures, as shown and described.

DESCRIPTION

FIG. 1 is an isometric view of a jaw rest for patient use during dental procedures showing my new design;

FIG. 2 is an isometric view of a second embodiment thereof;

FIG. 3 is a front view of the jaw rest for patient use during dental procedures of **FIG. 1**;

FIG. 4 is a rear view of the jaw rest for patient use during dental procedures of **FIG. 1**;

FIG. 5 is a front view of the jaw rest for patient use during dental procedures of **FIG. 2**;

FIG. 6 is a rear view of the jaw rest for patient use during dental procedures of **FIG. 2**;

FIG. 7 is a bottom view of the jaw rest for patient use during dental procedures of **FIG. 2**;

FIG. 8 is a top view of the jaw rest for patient use during dental procedures of **FIG. 2**;

FIG. 9 is a bottom view of the jaw rest for patient use during dental procedures of **FIG. 1**;

FIG. 10 is a top view of the jaw rest for patient use during dental procedures of **FIG. 1**;

FIG. 11 is a side view of the dental jaw rest for patient use during dental procedures of **FIG. 1**, the opposite side being a mirror image; and,

FIG. 12 is a side view of the jaw rest for patient use during dental procedures of **FIG. 2**, the opposite side being a mirror image.
